UNITED STATES PATENT OFFICE.

SAMUEL R. KRAMER, OF PERKASIE, PENNSYLVANIA.

ATTACHMENT FOR PRINTING-PRESSES.

SPECIFICATION forming part of Letters Patent No. 779,367, dated January 3, 1905.

Application filed June 10, 1903. Serial No. 160,893.

To all whom it may concern:

Be it known that I, SAMUEL R. KRAMER, a citizen of the United States, and a resident of Perkasie, Pennsylvania, have invented certain 5 Improvements in Attachments for Printing-Presses, of which the following is a specification.

My invention relates to certain improvements in the detail construction of auxiliary 10 mechanism for attachment to printing-presses; and it more particularly consists in an improved winding device for controlling the passage of a continuous web of paper to or from a roll upon which the same is wound, the main object of the invention being to provide a structure which while tending continuously to wind 15 up or draw out a web of paper shall be so designed that the web will be acted upon only when a predetermined amount of it has accumulated at a given point.

A further object of the invention is to provide easily-adjustable means for maintaining any desired degree of tension upon a web of paper or similar material.

25 These objects I secure as hereinafter set forth, reference being had to the accompanying drawings, in which—

Figure 1 is a side elevation showing the preferred form of my improved winding or feed-controlling apparatus. Fig. 2 is a plan view of the device, showing the arrangement of rollers and also illustrating the preferred construction of adjustable clutch; and Fig. 3 is a side elevation on the line 3-3, Fig. 2, showing 30 an improved means for keeping the printed surface of the web of paper out of contact with certain of the rollers.

In the above drawings, A and A are a pair 40 of frames suitably held together by a series of tie-bolts and provided with bearings for the support of rollers, of which two are shown at a' and a''. A shaft a³ is carried on what is in the present instance the highest portion of the frames A, and said shaft has carried 45 loosely on it a pulley a⁴, placed to receive a belt a⁵, connected to a source of power, which belt is omitted from Fig. 2 for the sake of clearness. To this pulley is fixed a conical section b, and there are bearing upon said 50 section shoes b', pivotally carried on bars b'',

which in turn are pivotally supported by a cross-piece b³, fixed to the shaft a³. In Fig. 2 it will be noted that the bars b² extend beyond the points of their attachment to the cross-bar b³ and rest upon the conical surface 55 of the adjustable piece b⁴, which piece is threaded upon an extended portion of the shaft a³, so that it may be moved from the cross-bar b³, and thereby force farther apart the adjacent ends of the bars b², thereby causing 60 the opposite ends of said bars to press the shoes b' upon the conical section b.

Upon the shaft a³ is wound a web of paper, (indicated at c,) the same forming a roll C, which in the particular device illustrated is 65 so operated as to wind up or have added to it the said web. This extends from the roll C between the two rollers d' and d'' to and between the other rollers d and d', and I preferably carry both of said pairs of rollers in 70 bearings formed in the frames A in such manner that the upper one of each pair is free to rise or fall in its bearings. Upon an extension of the supporting-shaft of the roller d is fixed a toothed wheel d².

Pivoted to one of the frames A at e is a lever E, having at its end a pair of arms e' and e'', and the upper of said arms is so formed as to come into the path of and engage with the teeth of the wheel d². The second arm, e'', 80 which is at the end of the lever E, has projecting from it two pins e³ and e⁴, while the opposite end of said lever is provided with an extension upon which is adjustably carried a weight e⁵.

While the roll d³ is carried in fixed bearings in the frames A, the bearing d⁴ is carried by a pair of arms d⁵, one of which, as shown in Fig. 1, extends between two pins or projections e³ and e⁴, projecting from the arm e² of 90 the lever E.

In order that the web of paper c shall not have its printed surface brought in contact with the faces of the rolls over which it passes, I provide a pair of relatively narrow bands f, 95 which pass around the roller a' and over the roller a'', down to and around the roller b, thereby preventing the rollers d and d' and a' and a'', respectively, from approaching nearer one another than the thickness of said band. 100

In operation a pair of bands are so placed upon the above-mentioned rollers as to bear upon the extreme margins or edges of the web of paper, thereby preventing the printed portion of said web from coming in contact with the rolls *d* and *a*.

It is to be understood that in the form of printing-press to which my winding device is designed to be attached the web *c* is fed intermittently, and with the various parts of the apparatus in the positions indicated in Fig. 1 the belt *a*⁵ continuously turns the pulley *a*³ through the medium of the shoes *b*' and *b*² and cross-arms *b*³, said pulley consequently exerting a force upon the shaft *a*³, whereby the web *c* is constantly under a tension, which may be regulated by means of the adjustable conical nut *b*⁴. The result of this construction and operation is that as soon as there is any slack in the paper web *c* this will be immediately taken up upon the roll *C*. As soon as the web is fed forward in the direction of the arrow in Fig. 1 the roller *d*⁴ immediately falls and one of its supporting-arms *d*⁵ comes in contact with the pin *e*⁴. As said roller is of appreciable weight, the result of such action is to move the lever *E* upon its pivot *e*, thus also moving the arm *e*' of said lever out of engagement with the teeth on the wheel *d*². Said wheel and the roller *d* are now free to rotate and the web *c* is wound upon the roller *C* until sufficient of the slack in said web has been taken up to raise the roller *d*⁴ high enough to bring the arm *d*⁵ into contact with the pin or projection *e*³, and thereby again turn the lever *E* upon its pivot, so as to bring the end of the arm *e*' into engagement with the teeth on the wheel *d*². Further take up of the web *c* is now prevented until the roller *d*⁴ has again dropped far enough to engage and move the lever *E* through the medium of the projection or pin *e*⁴.

The weight *e*⁵ is adjustably carried upon one of the arms of the lever *E* so as to properly balance the weight of the other arms and projections, it being desired that the lever as a whole shall be so balanced upon its pivot as to remain in any given position without inherent tendency to move.

50 I preferably provide an idler-pulley *g* whereby any tightness of the bands *f* may be varied, this pulley being supported upon a shaft *g*', which is carried in bearings on arms *g*², adjustably clamped to the frame of the machine. I similarly provide an idler-pulley *a*⁷, carried upon an arm *a*⁸, to regulate the tightness of the belt *a*⁵.

I claim as my invention—

1. A device for controlling the amount of slack in a web of material, the same consisting of an arm, a piece carried thereby and active upon the web, with mechanism constantly tending to move said web, means for positively holding the web to prevent it from being moved by said mechanism and a device

placed to be acted on by the arm and connecting said arm and the web-holding means, substantially as described.

2. The combination of a device for exerting tension upon a web of material, means for preventing feeding of said web to said tension-exerting device, said preventing means including a device for locking or releasing the web, a piece held in a loop of the web, means connecting said piece with the locking and releasing device so as to permit feeding of the web when the loop therein is of relatively great length and to prevent said feed after said loop has been shortened by a predetermined amount, substantially as described. 80

3. The combination of a device for exerting tension on a web of material, a roller controlling the feeding of the web, a piece extending in a loop of the web and free to rise and fall, and means connecting the piece with the feed-controlling roller in such manner that after said piece has been lifted to a predetermined distance, said roller is locked from motion and retained in said locked condition until said piece has fallen a predetermined distance, substantially as described. 90

4. The combination of means for exerting tension upon a web of material, a roller controlling the feeding of said web, a toothed wheel attached to said roller, a frame having a piece engaging the loop in the web, and a bar connecting said arm with the toothed wheel, said parts being so placed that the wheel and its roller are prevented from turning when said arm is in one position and permitted to turn 100 when the arm is in another position, substantially as described.

5. The combination of a device for exerting tension upon a web of material, a roller having operatively connected to it a toothed wheel, 105 an arm carrying a piece in engagement with the web and a pivoted bar having portions for engagement by said arm at two points in its path of motion, said bar being placed to engage the toothed wheel, substantially as described. 110

6. The combination of a supporting-standard, a device for exerting tension upon a web of material, a roller carried in bearings on said standard, an arm pivoted to the standard and carrying a second roller in contact with the web of material and a bar acted upon by said pivoted arm at two points in the path of motion of said arm, with a device actuated by said bar to allow or prevent motion of said roller, substantially as described. 120

7. The combination of a pulley connected to a source of power, a spindle operatively connected to a web of material, means connecting said spindle and the pulley, whereby the tension put upon said web of material may be varied, a roller in engagement with said web of material having means for resisting the tension put upon the web, and a device releasing or locking said roller and constructed to be 130

operated by variations in the amount of web fed from said supply device, substantially as described.

8. The combination of a device for exerting tension upon a web of material, a frame for carrying the same, a pair of rollers engaging said web, a pair of feed-rollers beyond said guide-rollers, means for controlling the action of said feed-rollers, said means including a device, operated by variations in the quantity of web supplied to the feed-rollers, for locking or releasing said rollers, substantially as described.

9. A device for controlling the amount of slack in a web of material, the same including

a piece having means whereby it is supported so as to be in contact with the web, mechanism constantly tending to move the web, means for positively holding said web to prevent it from moving under the action of said mechanism and a device connecting said holding means and the piece in contact with the web, substantially as described.

In testimony whereof I have signed my name to this specification in the presence of two sub-²⁰scribing witnesses.

SAMUEL R. KRAMER.
